DESIGN FOR A DRESS

Elfrieda Hannah, New York, N. Y., assignor to Franklin Simon & Co., Inc., New York, N. Y.

Application July 29, 1936, Serial No. 64,123

Term of patent 3½ years

To all whom it may concern:

Be it known that I, Elfrieda Hannah, a citizen of the United States of America, residing in Manhattan, county of New York, and State of New York, have invented a new, original, and ornamental Design for a Dress, of which the following is a specification, reference being had to the accompanying drawing, forming part thereof, wherein,

The lines appearing between the two diagonal lines in the blouse of the dress, and at the edge of the skirt, represent lattice work.

I claim:

The ornamental design for a dress, substantially as shown and described.

ELFRIEDA HANNAH.
